Primary Examiner — Deanna L Pratt

(74) Attorney, Agent, or Firm — Thomas G. Peterson;
Bradley Arant Boult Cummings LLP(57) **CLAIM**

The ornamental design for a seat, as shown and described.

DESCRIPTION

FIG. 1 shows a perspective view of the seat in accordance with the new design.

FIG. 2 shows a front elevation view of the seat.

FIG. 3 shows a rear view of the seat.

FIG. 4 shows a top view of the seat; and,

FIG. 5 shows a side view of the seat.

The broken line showing of stitching on the arm of the seat in FIG. 5 illustrates stitching that forms a part of the claimed design.
